Solomon L. Cohen

United States Patent Office.

SOLOMON L. COHEN, OF NEW YORK, N. Y., ASSIGNOR TO LAWRENCE & COHEN, OF SAME PLACE.

Design No. 4,537, dated December 27, 1870.

DESIGN FOR THE BACK OF A PLAYING-CARD.

The Schedule referred to in these Letters Patent and making part of the same.

To all whom it may concern:

Be it known that I, SOLOMON L. COHEN, of the city, county, and State of New York, have invented a new Design for the Backs of Playing-Cards, of which the following is a specification, reference being had to the accompanying drawing, which represents the back of a card on one-half of which my design is printed.

The back of the card is divided transversely into two equal parts or halves, on each of which is to be represented the design.

The central figure or device of the design consists of the Prussian eagle. From behind the wings of this there diverge the staffs of two German national

flags, which form the flanking portions of the design. The space between the two flag-staffs above the eagle is occupied by representations of gun-barrels, bayonets, and interposed rays of light, all radiating from the center of the card.

What I claim, and desire to secure by Letters Patent, is—

The design for the back of a playing-card, as shown and described.

SOLN. L. COHEN.
